ABSTRACT

A shock absorbing device for a boat seat supported by a link system to move vertically downwardly against the action of spring means and damping means cooperating with the link system to damp upward and downward movements of the seat.

SHOCK ABSORBING DEVICE FOR A BOAT SEAT

The present invention relates to a shock absorbing device for a boat seat supported by means of a linkage system having transverse pivot axes and adapted to permit vertical downward movements of the seat against the action of a pressure spring means located between the seat frame and a base supporting the linkage system.

Motorboats, when travelling at high speed, are regularly subject to violent blows and shocks as a result of the effect of waves against the hull of the vessel. Such shocks are particularly manifest in choppy water and are in part propagated to the seats of the boat, causing discomfort and, on occasion, pain to persons seated therein.

The present invention provides a shock absorbing device for a boat seat which reduces the shocks which are being transmitted to the occupants thereof. The device according to the invention is characterized in that the linkage system comprises a forward pair of parallel spaced link arms pivotable at their lower ends about a first common pivot axis and a rearward pair of parallel spaced link arms pivotable at their lower ends about a second pivot axis, the lower ends of the link arms at one side of the seat being interconnected by a synchronizing link member so as to provide synchronous movements up and down of the forward and the rearward pairs of link arms, the upper ends of the link arms being hingedly connected to the seat frame through link members and the upper end portions of the link arms which are connected through link rods with the ends of a lever arm which is journaled between its ends on a supporting member secured to the seat frame.

The invention will now be described in more detail with reference to the accompanying drawing in which

FIG. 1 is a side view of a boat seat provided with a shock absorbing device according to the present invention,

FIG. 2 is a view of the shock absorbing device seen from the opposite side to that shown in FIG. 1,

FIG. 3 is a back view of the device of FIGS. 1 and 2, and

FIG. 4 is a separate view of a number of elements which according to FIG. 1 are effective in retarding upward movement of the boat seat.

In the drawing, numeral 1 designates a base plate which is preferably of a nonmagnetic material. Secured to the base plate are two bearing brackets 2a, 2b for a linkage system supporting a seat frame 7 with the seat so as to permit vertical movements of the seat.

A pressure spring means 20, FIG. 3, in the form of a helical coil spring is located between the seat frame 7 and the base plate 1 to retard downward movements of the seat.

The linkage system comprises a forward pair of parallel spaced link arms 3a, 3b which at their lower ends are pivotable about a first common pivot axis 3c. There is also a rearward pair of parallel spaced link arms 3d, 3e, which at their lower ends are pivotable about a second common pivot axis 3f.

The upper ends of the arms 3a, 3b are connected by a horizontal shaft member 3g, and the upper ends of the arms 3d, 3e are connected by a horizontal shaft member 3h.

As will be seen from FIG. 1, the lower ends of the link arms 3a, 3d at one side of the seat are formed with lugs 4a, 4b which are directed in the same sense of rotation about the pivot axis 3c and 3f, respectively. The lugs 4a, 4b are interconnected by a synchronizing link member 4 so as to provide synchronous movements up and down of the forward and the rearward pairs of link arms as will be understood from the drawing.

The upper ends of the link arms are journaled by means of the members 3g and 3h in bearing members 5 attached to transverse plates 6, 6a which are hinged by means of hinge

members 8 to the frame 7 of the seat to form link members between the frame 7 and the link arms 3a, 3b, 3d, 3e.

In order to prevent horizontal movement of the seat frame 7, the upper end portions of the link arms 3a and 3d are connected through link rods 19, 19a with the ends of a lever arm 17 which is journaled between its ends at 17a on a supporting member 17b secured to the seat frame 7.

In order to damp upward movements of the seat the two link arms 3a, 3d at one side of the seat cooperate with two elastic bushings 16, 16a mounted on a substantially horizontal rod 13. Each bushing is located between two washers 12 and 15 on the rod, the outer washer 12 being mounted on the adjacent link arm 3a and 3d, respectively, by means of a pin 12a rotatably mounted in the link arm. The washers 12 have a center hole to permit the rod 13 to slide freely therein. The other washers 15 are adjustable to any desired position along the rod 13 by means of nuts 14 to obtain any desired initial compression of the bushings 16, 16a.

In order to damp downward movements of the seat each of the two link arms 3e, 3b, FIG. 2, at one side of the seat pivotally support a curved buffer arm 9 and 9a, respectively, extending downwardly and having its substantially horizontal free end resting on an elastic buffer member 10 and 10a. The free ends of the two buffer arms may be pressed downwardly by a common adjusting means in the form of a nut 11a screwed on a screw 11 secured to the plate 1 so as to vary the initial compression of the buffer members 10 and 10a.

Thus the damp members 16, 16a and 10, 10a are easily adjustable for the weight of the person using the seat and for obtaining any desired damping effect.

What I claim is:

1. A shock absorbing device for a boat seat supported by means of a linkage system having transverse pivot axes and adapted to permit vertical downward movements of the seat against the action of a pressure spring means located between the seat frame and a base supporting the linkage system, characterized in that the linkage system comprises a forward pair of parallel spaced link arms pivotable at their lower ends about a first common pivot axis and a rearward pair of parallel spaced link arms pivotable at their lower ends about a second common pivot axis, the lower ends of the link arms at one side of the seat being interconnected by a synchronizing link member so as to provide synchronous movements up and down of the forward and the rearward pairs of link arms, the upper ends of the link arms being hingedly connected to the seat frame through link members and the upper end portions of the link arms which are connected through link rods with the ends of a lever arm which is journaled between its ends on a supporting member secured to the seat frame.

2. A device according to claim 1, characterized in that upward movements of the two link arms at one side of the seat are damped by means of two elastic bushings mounted on a substantially horizontal rod, each bushing being located between two washers on the rod, the outer washer being mounted on the adjacent link arm and having a center hole to permit the rod to slide freely therein, whereas the other washer is adjustable to any desired position along the rod to obtain any desired initial compression of the elastic bushings.

3. A device according to claim 2, characterized in that each of the two link arms at one side of the seat pivotally support a buffer arm extending downwardly and having its free lower end portion resting on an elastic buffer member, the free ends of the two buffer arms being located adjacent each other and subjected to the action of common adjusting means provided to enable a desired initial pressure of the two buffer arms on the elastic buffer member.
